UNITED STATES PATENT OFFICE

164,123

PLASTIC WASTE RECEPTACLE

Benjamin Needleman, Philadelphia, Pa.

Application May 8, 1950, Serial No. 9,804

Term of patent 14 years

(Cl. D58—4)

To all whom it may concern:

Be it known that I, Benjamin Needleman, a citizen of the United States of America, residing at Philadelphia, Pennsylvania, have invented a new, original, and ornamental Design for Plastic Waste Receptacles, of which the following is a specification, reference being had to the accompanying drawing, forming a part hereof.

Fig. 1 is a front elevation of a plastic waste receptacle showing my new design;

Fig. 2 is a side elevation of the same;

Fig. 3 is a top plan view of the same;

Fig. 4 is a bottom plan view of the same; and

Fig. 5 is a vertical section on the line 5—5 of Fig. 2;

Fig. 6 is an enlarged cross section of one corner taken on the line 6—6 of Fig. 5.

I claim:

The ornamental design for a plastic waste receptacle, substantially as shown.

BENJAMIN NEEDLEMAN.
